Inventor,

Hiram Joseph Livergood.

UNITED STATES PATENT OFFICE.

HIRAM JOSEPH LIVERGOOD, OF BRANTFORD, ONTARIO, CANADA.

MIDDLINGS-PURIFYING MACHINE.

SPECIFICATION forming part of Letters Patent No. 389,091, dated September 4, 1888.

Application filed November 25, 1887. Serial No. 256,678. (No model.)

To all whom it may concern:

Be it known that I, HIRAM JOSEPH LIVERGOOD, of the city of Brantford, in the county of Brant, in the Province of Ontario, Canada, 5 have invented a new and useful Middlings-Purifying Machine, of which the following is a specification.

My invention relates to improvements in middlings-purifying machines in which a suction-fan and rotatory carriers or elevators operate in conjunction with vibrating tables, a separating-chamber, and a vibrating sieve.

The object of my improvement is to provide a mechanism by which pulverulent impurities 15 and fine particles of bran and fiber may be removed from the middlings without waste, and the flour thus rendered pure and white. These impurities can only be removed by currents of air and before the middlings come to the 20 bolting-cloth for further separation. If they are not removed before by the current of air, they will pass through the bolt-cloth with the middlings. The presence of these particles in the flour gives it a darker shade and materially lowers its grade and value in the market. 25 I attain this object by the mechanism illustrated in the accompanying drawings, in which the same letters of reference indicate the same or corresponding parts.

30 Figure 1 is a vertical longitudinal section of a machine embodying my invention. Fig. 2 is a top view as the machine appears after the removal of the air-chamber. Fig. 3 is a view of the eccentric which operates the vibrating tables. Fig. 4 is a view showing the spider with a bucket attached to each arm. Fig. 5 is a detail view showing the ends of separating-chamber and pitman-connection to the vibrating tables.

40 The object of this invention is to improve the construction of the middlings-purifier for which Letters Patent No. 266,296 were granted to me October 24, 1882, so as to make it more effective in operation.

45 A is the frame of the machine. The top rails of the frame are rabbeted out, so that the flat deck T sets level with the face of the top rail. Through this deck or floor are holes cut for the admittance of air to the separating-chamber 50 S. Over these holes the valves V are placed for the purpose of regulating the air-current to the separating-chamber. The separating-

chamber S sits on the deck T. The air-chamber C sits on the separating-chamber S. Within this separating chamber S are a series of inclined lattices, G, and a series of inclined deflector-boards arranged alternately with the lattices, and forming with them and the floor T a series of approximately V-shaped hoppers, P.

M is a shaft extending longitudinally of the separating-chamber S, to which are fastened the spider-arms O, traveling in the hoppers P P, each of which is provided with a lifting-bucket, Q, at its outer end. These buckets 60 are formed so as to have a side discharge, and as they rotate in close proximity to the lower edges of the deflector-boards H they each scoop up the material in one of the hoppers P and deliver it to the inclined shaking tables 70 N, arranged a short distance above the tops of the deflector-boards H, from whence the material falls on the next lattice G, and the operation is repeated. Each of these tables N is supported by a strip of band-iron, N², which 75 extends through and a little way beyond the sides of the separating-chamber S in notches cut for that purpose. To each strip N² is fastened one end of a pitman, Z, which is attached at the other end to a lever, L, pivoted in one 80 side of the separating-chamber, as shown in Fig. 5. A bar, R, is attached to all the levers L, and is connected by a rod, J, to an eccentric, F, mounted on the fan-shaft X, so that the revolution of the latter imparts an end 85 shake to the tables N.

I do not wish to confine myself to the above method of driving the tables N, for in place of the eccentric F on the fan-shaft X a pulley 90 may be used, and in the place of the bar R a 90 shaft may be used. In this latter case a belt would run down from the pulley on the fan-shaft to a pulley on the shaft on a quarter-twist, and eccentrics would be used on the said shaft to give the tables N a lateral vibrating 95 motion. Each pitman Z would then be connected to an eccentric on the said shaft at one end and to the band-iron N² at the other end.

On one end of the separating-chamber S is located a feed-hopper provided with a feed-roll, E, and connected with the other end is a fan-chamber provided with a fan, B, mounted on the shaft X. This shaft receives motion from any suitable motor and communicates it

to all the moving parts of the machine. By means of a pulley and a belt it drives the shaft U, which in turn drives the shaft M and feed-roll E, the former by means of the bevel gear-wheels U and the latter by a belt.

The operation of the machine is as follows: The revolution of the feed-roll E causes the middlings to feed out of the hopper. They then fall in a thin sheet on the first inclined lattice G, and as they fall are struck by a current of air drawn in through the valves V, and thence through the first lattice G, which current of air carries off to the fan a portion of the light fluffy particles of bran and other impurities. When the middlings reach the bottom of the first interior hopper P, they are lifted up by the buckets Q and dropped onto the first shaking table N, which by its motion delivers the middlings in a thin sheet to the second lattice G. This operation is repeated until the middlings have reached to the last hopper P, from whence they are delivered through an opening in the deck T to the shaking separator D, to be operated on in the usual manner. Each of the valves V is independently adjustable, so that the force of the draft in different parts of the separating-chamber can be regulated.

I claim—

1. In a middlings-purifying machine, the combination of the separating chamber S, the feed-hopper, the feed-roll E therein, the shaft M, the lifting-buckets Q, mounted on said shaft, the inclined lattices G, and deflector-boards H, forming with the lattices G and floor T of the separating-chamber S the hoppers P, and the fan B, substantially as described.

2. In a middlings-purifying machine, the combination of the separating-chamber having valves V in its floor T, the shaft M, having spider-arms provided with lifting-buckets Q, secured thereon, the inclined lattices G, the inclined deflector-boards H, forming with lat-

tices G and floor T the approximately V-shaped hoppers P, and the fan B, substantially as described.

3. In a middlings-purifying machine, the combination of the separating-chamber, the feed-hopper, the feed-roll therein, the shaft M, the spider-arms provided with the lifting-buckets Q, secured thereon, the inclined lattices G, the deflector-boards H, the shaking tables N, and the fan B, substantially as described.

4. In a middlings-purifying machine, the combination of the separating-chamber provided with valves V in its floor T, the feed-hopper, the feed-roll E, journaled therein, the inclined lattices G, the inclined deflector-boards H, forming with the said lattices G and floor T the approximately V-shaped hoppers P, the shaft M, journaled longitudinally of said separating-chamber, spider-arms O, secured to said shaft, the lifting-buckets Q, having a side delivery fastened to said arm, means for revolving said shaft, inclined shaking tables N, located above said deflector-boards H, and a fan, B, connected to the air-chamber C at the opposite end from the feed-hopper, substantially as described.

5. In a middlings-purifying machine, the combination of the separating-chamber, the fan B at the rear end thereof, the shaft U, a feed-hopper at the end of separating-chamber S opposite to the fan, a feed-roll, E, journaled therein, the shaft M, journaled longitudinally of the separating-chamber S, the lifting-buckets secured thereon, the inclined lattices G, the deflector-boards H, forming with the lattices G and floor T of the separating-chamber S the hoppers P, the inclined shaking tables N, the mechanism for operating the same, and gearing connecting the moving parts, substantially as specified.

HIRAM JOSEPH LIVERGOOD.
